LAMP SOCKET

Application filed April 13, 1928. Serial No. 269,629.

This invention relates to electric lamp sockets of that type from which a lamp cannot readily be stolen or removed by unauthorized persons.

5 Lamp sockets of this type have been proposed in which the threaded shell or socket proper, into which the base of the lamp screws, is swiveled. Ratchet mechanism is employed to hold the shell stationary when 10 the lamp is inserted in the threaded shell, but if an attempt is made to remove the lamp the shell turns with it thus preventing removal of the lamp from the shell. Special provision is made for removing the lamp by au- 15 thorized persons when it is desired to do so, such as a key adapted to be inserted into the socket to operate certain mechanism for locking the threaded shell against rotation when it is desired to remove the lamp. Sockets of 20 this type have not been wholly satisfactory because their construction departs too much from the usual standard type of socket now in use which is quite simple and practical. The alterations which it has been necessary to 25 make in the simple standard socket in order to produce a socket of the type described above have been too expensive and too far reduce the practicability of the socket.

30 Other lamp sockets have been proposed in which the lamp may be locked in the socket by means of a set screw. While this type may be simpler in construction than the type described above, nevertheless, its design departs materially from the standard simple socket. 35 Among its other disadvantages is the fact that it is not entirely reliable as the bite of the set screw on the threaded base of the lamp may in some cases be loosened simply by the effort used in attempting to remove the 40 lamp.

45 Many other attempts have been made to provide a lamp socket from which the lamp cannot readily be removed, but so far none has been sufficiently practical to bring that type of socket into more than limited use.

50 The main object of this invention is to overcome the disadvantages of proposed lamp sockets of the foregoing type and to make available a lamp socket of this type so

constructed that it is thoroughly practical and adapted for general and extensive use.

Another object of the invention is to provide a lamp socket of the foregoing type which is simple in construction, less expensive to manufacture, and more practical than lamp sockets of this type heretofore proposed. 55

An additional object of the invention is to provide a lamp socket of the swiveled-shell type described above having simplified, less expensive and more efficient and practical means for mounting the threaded shell so that it can swivel, a further object in this direction being to supplement the improved 60 swivele mounting with simplified means for holding the threaded shell against rotation in one direction to permit the lamp to be inserted in the shell, while permitting it to rotate freely in the opposite direction to prevent removal of the lamp from the shell. 65

70 It is also an object of the invention to provide a lamp socket of the swiveled-shell type described above, in which means for permitting removal of the lamp by authorized persons when desired is of such simplified construction that only a very slight modification of the outer shell of the standard lamp socket is necessary. 75

75 A lamp socket constructed in accordance with the invention is illustrated in the accompanying drawings in which

Fig. 1 is a side elevation partly in section of the improved socket;

Fig. 2 is a plan view illustrating how the 85 swivel mounting of Fig. 2^a can be made from a stamping if desired;

Fig. 2^a is a perspective view of the completed swivel mounting for the threaded shell; 90

Fig. 3 is a perspective view of the threaded shell;

Fig. 4 is a horizontal section taken on the line 4-4 of Fig. 1;

Fig. 5 is a horizontal section illustrating 95 the manner in which the lamp may be removed by the use of a special tool;

Fig. 6 is a perspective view of the special tool; and

Figs. 7 and 8 are partial side views show- 100

ing modifications of the construction of the outer shell.

The preferred form of the socket shown in the drawings comprises an outer shell 1 which is of the usual or standard construction except for the slight modification to be herein-after referred to. The shell is lined with the customary sleeve 2 of insulating material. The upper part of the shell houses the usual porcelain block 3 or equivalent support for the internal parts. A cap 4 is detachably applied to the upper end of the shell 1 in the usual manner.

Within the lower part of the shell 1 is located the threaded shell or socket proper 5. Ordinarily this shell would be rigidly secured to the porcelain block 3 by means of screws 6 but according to this invention these screws, instead of being employed to hold the shell 5 rigidly to the block 3, are employed to fasten to the said block a ring 19 shown in perspective in Fig. 2^a. This ring has a pair of inturned lugs 7 provided with holes 8 to enable the ring to be attached to the block 3 by means of the screws 6. The ring is provided with a U-shaped slot or cut so as to form a tongue 9 which is bent inwardly to a slight extent so that it has a tendency to project towards the axis of the ring. The entire ring structure shown in Fig. 2^a may be made of thin sheet metal such as phosphor bronze, or the like, and may be stamped in one piece in strip form as shown in Fig. 2 and then curved to its ring form, the ends of the strip being united by solder or the like. According to this procedure the lugs 7 at this stage would be standing vertically upward. The upper edge of the threaded shell 5 has an outwardly extending flange 10. The ring shown in Fig. 2 is just large enough to receive the shell 5 so that the shell will turn freely in the ring. In assembling the device the shell may be passed downwardly through the ring 19 until the flange 10 engages with the upper edge of the ring as shown in Fig. 1. The lugs 7 may then be bent inwardly to the position shown in Fig. 2 and then secured to the block 3 by means of screws 6. This attaches the whole assembly to the porcelain block 3.

An alternative way of assembling the shell 5 in the ring structure is as follows: Before securing the ends of the ring together as by means of solder, the lugs 7 may be bent inwardly to their final position after which the shell may be slipped sidewise into the ring and the extremities of the ring thereafter soldered together.

The part of the shell 5 which lies under the ring is provided with an opening 11 preferably shaped as shown in Fig. 3. When a lamp is inserted into the threaded shell 5 the shell will turn until the opening 11 reaches the tongue 9. The end of the tongue, due to its tendency to incline towards the

axis of the ring, will slide into the opening 11 and when the straight edge 11' of the opening reaches the base of the tongue the shell can turn no further. The lamp may then be screwed all the way into the socket. When an attempt is made to remove the lamp the shell 5, due to the friction between it and the base of the lamp, will turn with the lamp and the lamp cannot be removed. The tongue 9 and the opening 11 therefore constitute simple but effective ratchet mechanism for holding the shell 5 stationary when the lamp is inserted in the socket, but it permits the shell 5 to turn with the lamp when an attempt is made to remove the lamp.

In order to permit removal of the lamp by authorized persons the lower part of the shell 1 is provided with at least one pair of diametrically opposite openings or slots 12. These openings permit the use of a special tool 13 shown in Figs. 5 and 6 having inwardly extending extremities 13' which may be inserted in the openings 12. By inserting the extremities 13' of the tool in the openings 12 and applying a gripping pressure to the ends of the tool the insulating material 2 is pressed against the shell 5 and the shell is frictionally held from turning. When the shell 5 is so held from turning the lamp may be readily removed by turning it in a counter-clockwise direction. If desired the openings 12 in the shell may be normally closed by a rotatable ring 14 shown in Fig. 7. This ring may have a pair of openings, one of which is shown at 15, which are adapted to register with the openings 12 in the shell when the ring is turned. This ring simply constitutes a closure for the openings 12. It is not essential and may be discarded altogether. Instead of providing the shell with slots of the kind shown at 12 the shell may be weakened as by means of slots 16 (Fig. 8) to provide depressible portions 17 which may be pressed inwardly by the extremities 13' on the special tool. When these portions 17 are pressed inwardly the shell 5 is frictionally held stationary while the lamp is removed.

If desired the ratchet mechanism 9-11 may be omitted altogether so that the shell 5 will swivel in both directions. In this case when it is desired to insert a lamp into the socket the shell 5 may be held stationary by the use of the special tool 13. This arrangement would provide an extremely simple socket but it would be necessary to use the special tool whenever it is desired to insert a lamp in the socket.

The circuit connections to the lamp are not shown in the drawings nor is the switch mechanism completely shown because they form no part of the invention. It will be understood, however, that one of the screws 6 is electrically connected with one side of the circuit and current is therefore conducted to the ring and then to the shell 5. The

other side of the circuit is connected to the central electrode 18 in the usual manner. The electrical contact between the shell 5 and the ring in which it is mounted is facilitated by the tongue 9 which pressing inwardly acts as a brush and establishes good contact between the ring and the shell 5. It will be noted that every time the shell 5 is turned to its limit in a clockwise direction the tongue is forced inwardly by the rear edge 12 of the opening 11. This action preserves, and actually increases, the normal tendency of the tongue to press inwardly, thereby preserving a good electrical contact between the tongue and the shell (when the tongue is not in the opening 11), and also causing it to maintain its tendency to drop or slide into the opening 11 upon clockwise rotation of the shell.

It will now be seen that the improved socket does not depart materially from the standard lamp socket. Its outward appearance is practically the same as the outward appearance of an ordinary lamp socket except for the provision of the openings 12. These openings permit the lamp to be readily removed by authorized persons and constitute extremely simple means for the purpose. They may be formed in the shell of the socket simply by a drilling operation. The tool employed for permitting removal of the lamp is very simple in construction and may be made at small cost. As one tool may be used with a large number of sockets the tool may be disregarded in considering the simplicity, cost of manufacture and practicability of the socket.

There is only one additional part required in the socket, namely the ring in which the shell 5 is swiveled, and therefore the socket may be manufactured at a cost which is only slightly in excess of that of the standard socket. The construction of the threaded shell 5 departs slightly from the construction of the standard threaded shell due to the provision of the flange 10 and the opening 11, but these may be provided at slight expense.

Either the ratchet mechanism on the one hand or the openings 12 and tool 13 on the other hand constitute improved and simple means for enabling the lamp to be inserted in a socket of the swiveled-shell type. When the openings 12 and tool 13 are employed for enabling insertion of the lamp they at once constitute simple means for accomplishing this and at the same time constitute simple means for permitting the lamp to be removed by authorized persons. The ring constitutes simple and inexpensive means for swiveling the shell and the ratchet mechanism is of the utmost simplicity, but is entirely effective and efficient in its operation. So far as the main feature of the invention is concerned, i. e., the frictional holding of

the inner shell stationary while the lamp is removed, any suitable means may be employed as a swivel mounting for the inner shell. Moreover, so far as this main feature of the invention is concerned, it is immaterial whether the lamp is held in the inner shell by means of threads or by some equivalent means. The essential thing is that the inner shell or lamp-holding member should require a turning movement of the lamp in one direction to insert it in the lamp-holding member and a turning movement of the lamp in the opposite direction to remove it from the lamp-holding member and that the lamp-holding member be mounted to rotate in at least said last named direction. It is in connection with such a general arrangement that the provisions for allowing frictional holding or gripping of the lamp holding member are useful and advantageous.

I claim:

1. A lamp socket comprising an outer shell, an interior swiveled threaded shell, and means whereby said threaded shell may be frictionally held against rotation. 90

2. A lamp socket comprising an outer shell, an inner threaded shell mounted for rotation, and an insulating sleeve between the outer and inner shells, the outer shell being slotted to permit the insulating sleeve to be pressed against the inner shell to frictionally hold it against rotation. 95

3. A lamp socket comprising an outer shell, an inner threaded shell mounted for rotation, and an insulating sleeve between the outer and inner shells, the outer shell having a pair of diametrically opposite openings to permit the insulating sleeve to be pressed against the inner shell to frictionally hold it against rotation. 100

4. A lamp socket comprising an outer shell, an inner threaded shell mounted for rotation, an insulating sleeve between the outer and inner shells, and ratchet mechanism for holding the inner shell stationary when a lamp is screwed into it but permitting rotation of the inner shell when it is attempted to remove the lamp from the socket, the outer shell having a pair of diametrically opposite openings to permit the insulating sleeve to be pressed against the inner shell to frictionally hold it against rotation to allow authorized removal of the lamp. 110

5. A lamp socket comprising an outer shell, an inner threaded shell, an insulating block in the outer shell, and a swivel mounting for the inner shell comprising a tubular shaped ring encircling the inner shell and having straight walls arranged parallel with the walls of the inner shell, said ring having inwardly extending lugs adapted to be secured to the insulating block, said inner shell having a flange extending over the upper edge of said ring. 120

6. A lamp socket comprising an outer shell, an inner threaded shell, an insulating block in the outer shell, and a swivel mounting for the inner shell comprising a tubular shaped ring supported by said insulating block and encircling the inner shell, the walls of said ring being substantially straight and parallel with the walls of the inner shell and a shoulder on said inner shell extending over the upper edge of said ring to rotatably support the inner shell.

7. A lamp socket comprising an outer shell, an interior lamp-holding member which requires a turning movement of the lamp in one direction to insert the lamp therein, and which requires a turning movement of the lamp in the opposite direction to remove the lamp therefrom, said lamp-holding member being mounted to rotate with the lamp in at least said last named direction, and means whereby said lamp-holding member may be frictionally held against rotation.

8. A lamp socket comprising an outer shell, an interior lamp-holding member which requires a turning movement of the lamp in one direction to insert the lamp therein, and which requires a turning movement of the lamp in the opposite direction to remove the lamp therefrom, said lamp-holding member being mounted to rotate with the lamp in at least said last named direction, and an insulating sleeve between the outer shell and said lamp-holding member, said outer shell being slotted to permit the insulating sleeve to be pressed against the lamp-holding member to frictionally hold it against rotation.

In testimony whereof I affix my signature.
VERNON T. HOUGHTON.
